UNITED STATES PATENT OFFICE.

ALBERT GRILL, OF PITTSBURGH, PENNSYLVANIA.

DESIGN FOR A PUSH AND COASTER CAR.

55,608.

Specification for Design.

Patented July 6, 1920.

Application filed January 10, 1920. Serial No. 350,706. Term of patent 14 years.

To all whom it may concern:

Be it known that I, ALBERT GRILL, a citizen of the United States, residing at Pittsburgh, in the county of Allegheny and State of Pennsylvania, have invented a new, original, and ornamental Design for Push and Coaster Cars, of which the following is a specification, reference being had to the accompanying drawings, forming part thereof.

The figure is a perspective view of a push and coaster car, showing my new design.

The design embodies the ornamental configuration of a push and coaster car for children's amusement in imitation of an airplane.

The design comprises a wheeled fuselage; an empennage, or tail parts; a propeller; and wings. The fuselage is of substantial

dimensions, and the wings and empennage are in such proportion to the fuselage as to give a natural and pleasing effect.

It is to be understood that the design is not claimed as applied to a machine for flying or to one having any mechanical means of propulsion.

What I claim is:

The ornamental design for a push and coaster car, substantially as shown and described.

In testimony whereof, I have hereunto set my hand.

ALBERT GRILL.

Witnesses:

M. L. NEWELL,
G. W. ALSTON.
